CLAIM

The ornamental design for a movable platform for portable device holder, as shown and described.

DESCRIPTION

FIG. 1 is a perspective view of a movable platform for portable device holder attached to a portable device protective cover in a first position, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the movable platform for portable device holder of FIG. 1, attached to a portable device protective cover in a second position;

FIG. 9 is a perspective view of the movable platform for portable device holder of FIG. 1 in an alternative environment, attached to a portable device protective cover in the first position; and,

FIG. 10 is a perspective view of the movable platform for portable device holder of FIG. 1 in the alternative environment of FIG. 9, attached to a portable device protective cover in the second position.

The broken lines in FIGS. 1–10 depict portions of the movable platform for portable device holder and portable device protective cover that represent unclaimed environment and form no part of the claimed design.

1 Claim, 8 Drawing Sheets
